Primary Examiner—Caron D. Veynar

(74) Attorney, Agent, or Firm—Barry E. Deutsch, Esq.

(57) **CLAIM**

The ornamental design for a food processor housing, as shown and described.

DESCRIPTION

FIG. 1 is a perspective view, taken from the front, right side, and top, illustrating our new design of a food processor housing;

FIG. 2 is a top plan view thereof;

FIG. 3 is a right side elevation view thereof;

FIG. 4 is a rear elevation view thereof;

FIG. 5 is a front elevation view thereof;

FIG. 6 is a left side elevation view thereof; and,

FIG. 7 is a bottom plan view thereof.
